UNITED STATES PATENT OFFICE.

IRVING L. DEMPSEY, OF GALENA, MARYLAND, ASSIGNOR TO THE OLIVER TYPE-WRITER COMPANY, OF CHICAGO, ILLINOIS, A CORPORATION OF ILLINOIS.

TYPE-WRITING MACHINE.

1,115,653.

Specification of Letters Patent.

Patented Nov. 3, 1914.

Application filed April 11, 1913. Serial No. 760,373.

To all whom it may concern:

Be it known that I, IRVING L. DEMPSEY, a citizen of the United States, and a resident of Galena, in the county of Kent and 5 State of Maryland, have invented certain new and useful Improvements in Type-Writing Machines; and I do hereby declare that the following is a full, clear, and exact description thereof, reference being had to 10 the accompanying drawings, and to the letters of reference marked thereon, which form a part of this specification.

This invention relates to improvements in typewriting machines, and particularly to 15 mechanism for regulating the spacing of the lines of the work.

The object of the invention is to provide 20 a mechanism of this class by which the spacing of the written lines may be easily and quickly regulated.

Another object is to provide a mechanism which may be quickly regulated, so that any desired width of spaces between the written lines may be accurately secured.

25 With these and other objects in view, my invention consists of the following novel combination and arrangement of parts, shown in the accompanying drawings, set forth in the following description, and specifically pointed out in the claims hereto appended.

In the drawings—Figure 1 shows the end view of an Oliver typewriter carriage; Fig. 2 is a side view of the mechanism shown in 35 Fig. 1; Fig. 3 is a plan view of that portion of the mechanism used for regulating the space, namely, the single, double or triple space, or any intermediate space. Fig. 4 is a sectional view, taken on line 4—4 of 40 Fig. 2.

Referring to the drawings, the left-hand end-plate 1 of the carriage is therein shown, the features constituting my invention being located exterior to the same. The platen 2 is mounted in the ordinary manner upon the spindle 3, and carries at its outer end the usual hard rubber, knurled finger piece 4, which finger piece is mounted to slide endwise on said spindle. A spring 4^a, shown in 45 dotted lines in Fig. 2, acts to normally force the said finger piece away from the end plate 1. At the inner end of the said finger piece and rotatively secured thereto is a collar 5 slidable upon the spindle 3 by means of a

feather and spline, or any other preferred means which will lock said collar so that it will rotate with the spindle, and at the same time allow a sliding movement of the collar thereon. As shown in Fig. 4, the collar 5 is slidably secured to the spindle 3 by a screw or member 5^a inserted through said collar and having its inner end projecting into a longitudinal groove 3^a in said spindle. Diametrically disposed radial links 6 are pivoted to ears upon said collar 5, the outer ends of the links being in turn pivoted to levers 7, whose fulcrums 8 are located at the outer ends of oppositely disposed arms 9 upon a collar 10. One of the levers 7 passes through an aperture 7^a in an arm 13, 70 on which is formed, or to which is attached, the collar 10, and which turns upon the spindle 3. The free ends of the levers 7 are provided with gripping shoes 11 adapted to grip the peripheral surface of a wheel 12. 75 This wheel is provided with a corrugated or roughened peripheral surface. This provides a positive gripping surface which is adapted to be engaged by the grippers 11 when the typewriter carriage is being shifted to the right, to bring the same into position for starting to write the next line. As the arms 9 are mounted on the collar 10, the levers 7 which are pivoted to said arms, turn with the arm 13; the engagement of one of 80 said levers with said arm 13, serving to afford locking engagement of said lever with said arm. The movement of the carriage effects the line-spacing movement of the platen, as in an Oliver typewriter, the wheel 12 and the means employed for rotating the same being substituted for the platen turning device heretofore used on such typewriter.

As shown in the accompanying drawing, 95 the arm 13 has at its free or swinging end segmental rack teeth 14, which teeth engage teeth on a segment 15 pivotally supported at 16, in the usual manner. A lug 17 has pivoted thereto the usual operating rod 18, 100 said rod being slidable endwise in a bearing 19 secured to the typewriter carriage, and adapted for contact with an adjustable stop 20 secured in a bracket 21 upon a rod 22 carried by the typewriter frame in the 105 movement of the carriage to the right. This mechanism for adjusting the arm 13 is that usually employed in an Oliver type-

writer, as part of the means for automatically turning the platen for line spacing, each time the carriage is moved or shifted to the right, for starting a new line, and it 5 will be obvious from reference to Fig. 3 that the contact of the rod 18 with the stop 20 will cause the rotation of the segment 15 and a movement of the arm 13, and when the finger piece 4 is pressed toward the end 10 plate and the said arm is locked to the wheel 12 by means of the grippers 11, the operation of the parts will effect a partial rotation of the platen 2.

In order to determine or regulate the extent of rotary movement of the platen, there 15 is provided upon the plate 1 a graduated rod 23 arranged generally in a horizontal position at the rear of the arm 13, and constituting an adjustable stop member adapted for 20 limiting the extent of movement of said arm. Said rod is slideable endwise in bearings 24 and 24^a on the plate 1 and has a transverse arm 25, on its forward end, located in the path of movement of the arm 13. In the 25 lower surface of the rod 23, there are provided three notches 25^a adapted to engage a pin 26 upon the plate 1. In order that the machine may be set for either a single, double or triple space, it is only necessary to engage 30 the pin 26 in the proper notch 25^a which limits the movement of the arm 13, and consequently determines the extent of rotation of the platen 2, the arm 13 being locked to the platen by the shoes 11. A 35 spring 30 acts downwardly on said rod to hold the same in engagement with the pin 26, when the ordinary spacing is used.

In order to provide for a variable regulation of line spacing, the rod 23 is provided 40 with a series of graduations 27, a pointer 28 being mounted on the bearing 24^a in juxtaposition to said graduations. This is provided in order that the machine may be set to write upon ruled paper, irrespective of 45 the width of the spaces between the equally spaced lines on the same. This is accomplished by placing the ruled paper on a scale which may be provided upon the front of the machine, said scale corresponding with 50 the graduations on the rod 23, and setting or adjusting said rod in fixed position on the end plate, to correspond to the spacing between the lines. A set screw 29, inserted in the bearing 24, serves to hold the rod 23 in 55 any desired adjusted position, thereby affording variable line-spacing movement in the platen and permitting such line-spacing movement to correspond exactly with the spacing of the lines on the ruled sheet.

60 The usual pivoted arm 31 is utilized to carry a brake 32 for arresting the movement of the wheel 12. This brake is pivoted, at 33, at the outer end of said arm 31, and consists of a friction shoe 34, the said brake being 65 reversible and having a roller 35 which may

be brought into engagement with the wheel 12.

From the foregoing description, taken in connection with the accompanying drawings, it will be seen that I have provided a 70 simple and efficient means adapted to afford variable line spacing, but also adapted for use in effecting single, double or triple line spacing, when the spaces are of fixed or standard width.

75 While the construction shown and described is the preferred embodiment of my invention, it is, of course, understood that changes may be made in the form, proportion, and minor details of construction, without departing from the spirit or sacrificing any of the advantages of the invention.

I claim as my invention:

1. A line spacing mechanism, comprising a wheel turning with the platen, an endwise movable finger piece, gripping means mounted to turn concentrically with the platen, said gripping means being operated by the movement of said finger piece and engaging said wheel, a movably mounted stop-member 80 for limiting the movement of said gripping means when engaged with said wheel, means having locking engagement with said stop-member for holding the same in either one of a plurality of predetermined spaced 85 positions for unitary line spacing, and clamping means acting on said stop-member for holding the same in any desired position of adjustment to afford fractional line spacing.

2. A line spacing mechanism, comprising a wheel turning with the platen, an oscillating arm mounted to turn concentrically with the platen, a finger piece, gripping means adapted to be moved into and out of gripping engagement with said wheel by said finger piece, said gripping means having turning movement with said arm, an endwise movable rod connected with and carried by said platen, said rod having operative connection with said arm, the latter being oscillated upon the endwise movement of said rod, a stop located in the path of movement of said rod, and an endwise movable bar adapted for variably limiting the 100 movement of said arm.

3. A line spacing mechanism comprising a wheel turning with the platen, an oscillating arm mounted concentrically with the platen, a finger piece having endwise movement relatively to the platen, gripping means operated by the movement of said finger piece, said gripping means having turning movement with the said arm and being adapted for gripping engagement with the wheel, a movably mounted stop member for limiting the movement of the said arm, means having locking engagement with said stop-member for holding the same in either one of a plurality of positions, and 115 120 125 130

clamping means acting on said stop member for holding the same in any desired position of adjustment.

4. A line spacing mechanism comprising 5
5 a wheel attached to the platen shaft, an os-
cillating arm mounted on said shaft, a finger
piece movable endwise on said shaft, pivot-
ally mounted gripping levers connected and
moving with said oscillating arm, and links
10 connecting said levers with said finger piece.

5. A line spacing mechanism comprising
a wheel attached to the platen shaft, an os-
cillating arm mounted on said shaft and pro-
vided with a rigidly attached collar which
15 surrounds the shaft, opposite, radial arms
on said collar, levers pivoted to the said
radial arms and adapted for gripping en-
gagement with said wheel, a finger piece
20 mounted to slide on the platen shaft, and
links connecting the said levers with the said
finger piece.

6. A line spacing mechanism, comprising
a shaft, a platen mounted on said shaft, a
wheel mounted on said shaft and turning
25 with said platen, an oscillating arm mounted
on said shaft, pivotally mounted gripping
levers having turning movement with said
arm and being adapted for gripping engage-
ment with said wheel, an endwise movable
30 finger piece, links connecting said gripping
levers with said finger piece, means for oscil-
lating said arm, and an endwise adjustable
rod located on the carriage frame in the path
of movement of said arm.

35 7. A line spacing mechanism comprising
a shaft, a platen mounted on said shaft, a
wheel mounted on said shaft and turning
with said platen, an oscillating arm mounted
on said shaft, gripping levers having turn-
40 ing movement with said arm and being
adapted to engage said wheel, an endwise
movable rod located on the carriage frame
in the path of movement of said arm and
having notches therein, a fixed pin for en-
45 gagement with said notches, and a spring for
holding said pin in engagement with said
notches.

8. A line spacing mechanism, comprising
a shaft, a platen mounted on said shaft, a

wheel mounted on said shaft and turning 50
with said platen, an oscillating arm mounted
on said shaft, gripping levers having turn-
ing movement with said arm and being
adapted to engage said wheel, an endwise
movable rod located on the carriage frame, 55
in the path of movement of said arm, and
provided with graduations, a pointer acting
in connection with said graduations, and
means for holding the said rod in any de-
sired position of adjustment.

9. A line spacing mechanism, comprising
a shaft, a platen mounted on said shaft, a
wheel mounted on said shaft and turning
with said platen, an oscillating arm mounted
on said shaft, gripping levers having turn- 65
ing movement with said arm and being
adapted to engage said wheel, an endwise
movable rod located on the carriage frame
in the path of movement of said arm, means
having interlocking engagement with said 70
rod for holding the same in a plurality of
equally spaced positions for unitary line
spacing, and means for holding said rod in
any desired position of endwise adjustment
to afford fractional line spacing.

75 10. A line spacing mechanism, comprising
a shaft, a platen mounted on said shaft, a
wheel mounted on said shaft and turning
with said platen, an oscillating arm mounted
on said shaft, gripping levers having turn- 80
ing movement with said arm and being
adapted to engage said wheel, an endwise
movable rod located on the carriage frame
in the path of movement of said arm, said
rod having a plurality of equally spaced 85
notches, a pin adapted for engagement with
either of said notches, and clamping means
acting on said rod to hold the same in any
desired position of adjustment.

In testimony, that I, claim the foregoing 90
as my invention I affix my signature in the
presence of two witnesses, this first day of
April A. D. 1913.
